COMBINATION FLOWER BASE AND CANDLE HOLDER

Mildred M. Hennig, 5433 Edelweiss Lane, St. Louis, Mo.

Filed Nov. 29, 1963, Ser. No. 77,610

Term of patent 14 years

(Cl. D35—3)

I claim:

The ornamental design for a combination flower base and candle holder, as shown and described.
